UNITED STATES PATENT OFFICE.

GEORGE C. OLMSTED, OF MINNEAPOLIS, MINNESOTA.

AUTOMATIC INTERMITTENT CONTROL FOR INTERNAL-COMBUSTION ENGINES.

1,269,637.

Specification of Letters Patent. Patented June 18, 1918.

Application filed March 9, 1917. Serial No. 153,787.

To all whom it may concern:

Be it known that I, GEORGE C. OLMSTED, a citizen of the United States, residing at Minneapolis, in the county of Hennepin and 5 State of Minnesota, have invented certain new and useful Improvements in Automatic Intermittent Controls for Internal-Combustion Engines, of which the following is a specification, reference being had therein 10 to the accompanying drawing.

This invention consists of certain improvements in devices for automatically preventing freezing of an automobile engine or the rendering of said engine and 15 parts inoperative by the action of cold, the annoyance and inconvenience in addition to frequently much damage and expense being well known to the owners of automobiles.

The invention relates especially to that 20 class of automobiles equipped with electric self starters, the device being principally electrically controlled and made to operate in connection with the electric equipment of the automobile.

25 The principal object of the device is to produce a practical and reliable mechanism that may be depended upon to intermittently set the engine of the automobile in motion and keep it running for a predetermined period.

Another object is to provide such a device, 30 automatically controlled by atmospheric temperature.

Other objects and advantages will appear 35 in the further description of the invention.

In the accompanying drawings forming part of this application and in which like reference characters indicate like parts:

Figure 1 represents a diagrammatic view 40 of the novel combination of operative elements essential in carrying out my invention.

Fig. 2 is an enlarged diagrammatic view 45 of the thermometer used in the automatic circuit.

Fig. 3 is a transverse sectional view of the 50 exhaust pipe of the engine showing in elevation the damper switch or circuit breaker in the starter circuit.

Fig. 4 is a longitudinal vertical section 55 of Fig. 3.

Fig. 5 is a diagrammatic plan view of the

automatic magnetic switch used in the starter by-pass circuit.

Fig. 6 is a side elevation of the clock operated controlling mechanism, and

Fig. 7 is a plan view of Fig. 6.

In the ordinary operation of an automobile engine equipped with an electric starter, the engine is started by first closing the engine switch ready for proper ignition, assuming that the proper supply of gas is provided, then the starter switch is closed. This by virtue of proper connection with the stored supply of electricity will excite 65 the starter motor into action and it being geared to the engine shaft will start the engine, meanwhile the spark and throttle levers being adjusted to proper positions will supply fuel and ignition to the engine, 70 thus enabling same to run so long as these are supplied.

In the drawings, 1 represents the engine of the automobile, 2 the electric generator which is driven by the engine and furnishes 75 a supply of electricity to the storage battery 3, and 4 represents the starter motor which derives its power from the storage battery 3 when required to start the engine. These together with their various switches 80 and connections which differ materially in different makes of cars though their functions remain the same, are found on the ordinary automobile.

In illustrating a practical embodiment of 85 my automatic coöperating combination with the above described elements, I provide an auxiliary electric circuit which is termed the operating circuit, and in which is installed a clock operated wheel 5, a metallic thermometer 6, a circuit breaker 7, automatic switches 8, and 50 an auxiliary two way switch 9 with certain electric contacts and connections hereinafter more fully described.

The gear wheel 5 is preferably of solid construction and operatively mounted in any desired manner to a common spring wound clock suitable for the purpose, and connected with the clock in such a manner 100 as to revolve, say, once in every 120 minutes. On one face of the wheel are several series of like projections or contact points 10 placed equidistant apart in different con-

centric circles, as for example, as illustrated, there are six such points in the outermost series, they representing spaces of time 20 minutes apart; in the next series there are 5 but three such points representing spaces of time 40 minutes apart; in the next series there are but two such points representing spaces of time 60 minutes apart, and in the last series there is but one such point representing a space of time of 120 minutes or one full revolution of the wheel during the interval between contacts.

The axle 11 of the wheel 5 is in the electric operating circuit as indicated at 12.

15 Spaced a distance from the face of the wheel 5 carrying the contacts 10, is a radially extending longitudinally adjustable arm 13 insulated from and carried upon a suitable fixed support, 14.

20 The end of the arm adjacent the face of the wheel 5 has a contact point 16 extending toward said wheel and which, when in the path of any of the points 10 will engage same as the latter pass thereunder.

25 The arm 13 is supported at its opposite end by a knobbed bolt 15 which passes through an elongated slot 17 in the support 14. A suitable spring washer 17' is positioned beneath the head of the bolt by which 30 the proper tension is maintained thereupon to admit of the arm being slid longitudinally as described.

An adjusting thumb screw 18 with suitable lock nut 19 may be installed intermediate the ends of the arm 13 and whereby the impingement of the contact point 16 upon the points 10 may be varied according to requirements by vertical adjustment of the screw 18, the resilient tendency of the arm 13 being normally toward the face of the wheel 5.

35 Formed integral with the base 14 or adjacent thereto is an indicator scale 20 having four equidistant points 21 thereupon, the 40 distance between said points being equal to the radial distance between any two of the contact points 10 radially alined on the wheel 5.

45 The points 21 are designated from the 50 wheel end of the plate 20, 120, 60, 40 and 20, which coincides with the radial spacing of the contact point 10 as previously described. A pointer 22 is fixed to the arm 13 adjacent the knobbed bolt 15 and by which 55 the longitudinal position of the arm 13 is determined as is obvious. The arm 13 is connected with and forms a part of the operating electric circuit as at 23. Thus the intermissions between closed periods of the 60 electric circuit may be regulated by the longitudinal adjustment of the arm 13 in positioning it to engage different series of contacts 10.

The metallic thermometer 6 installed 65 within the electric circuit is of the common

standard type depending upon the movement of strips of metal whose coefficients of expansion are different and which movement causes the spindle 23' to oscillate in accord therewith. To the index pointer 24, 70 I attach a spring metal extension 25. In a suitable support 26, spaced a distance from the extension 25 and in the path thereof, is screw threadedly mounted a thumb screw 27, said thumb screw extending normally at 75 approximately right angles to the extension 25. Parallel with the thumb screw 27 and abreast the head 28 thereof is a scale plate 29 having graduated marks along the edge thereof adjacent the peripheral edge of the head 28 of the screw 27. These scale markings are designated zero, 10 degrees below and 10, 20 and 30 degrees above zero, as indicated, or any other degrees desired may be indicated on the scale. The relative position of this plate, the thumb screw and extension 25 on the thermometer are such that when the head of the thumb screw is in line with the mark 10 degrees below zero, the extension 25 of the thermometer will 90 engage the end of the thumb screw adjacent thereto when the thermometer registers 10 degrees below zero. When such contact occurs, the two lines of the electric circuit being connected, one at 30 to the base of the 95 thermometer 6, and the other at 31 to the fixed support 26, the circuit will be closed. From the above it is evident that this device in connection with the thermometer may be set to operate at various temperatures. 100

The circuit breaker 7 comprises a transverse shaft 32 rockably mounted within the exhaust pipe 33 leading from the engine. From this shaft rigidly depends a substantially semi-circular shaped blade 34, said blade being but slightly smaller than the lower portion of the exhaust pipe in which it extends, for the purpose of being quickly affected by the exhaust passing through the 110 pipe. To one end of the shaft 32 extending outside of the exhaust pipe is rigidly fixed an upstanding metal arm 35, which is designed to simultaneously contact the two suitably arranged termini 36 and 37 of the 115 electric starter circuit, when the blade 34 is in its normal inactive lowermost position, as indicated in Fig. 4, thus closing the electric circuit in the wires 36 and 37. When the blade 34 is raised by the action of the 120 exhaust passing through the pipe 33, such electric connection will be broken by the arm 35 swinging from contact with the ends of the wires 36 and 37.

While I have shown this form of automatic circuit maker and breaker being operated by the exhaust of the engine, it is evident that other forms of a similar device operated by a moving portion of the engine might be resorted to and which depends for 130

its action upon the speeding up of the engine when it operates on its own fuel independent of the starter motor.

- 38 represents the regular engine switch 5 installed within the ignition circuit of the engine and which it is the custom to lock open to prevent theft of the car. Around this switch is the by-pass circuit 39-39, connected to either side of the electro-magnetic switch 50, which is installed within 10 the circuit intermediate of the thermometer 6 and the clock mechanism which control the ignition circuit, the switch 50 being automatically operated therein.
- 15 The auxiliary two way switch 9 is installed within the starter circuit so that the energy from the storage battery 3 may be cut out and electric energy from an exterior source be substituted therefor, as for example, 20 when the automobile is in a garage equipped with other electric energy, the object of this provision being to make the demand on the storage battery as light as possible.

•The starter by-pass automatic switch 8 in 25 the starter circuit is automatically operated by the closing of the operating circuit passing through the clock mechanism and the thermometer. The tongue 41 of the switch is drawn by electromagnetic force to contact 30 with the core 42 of the magnet 43, by the electric energy traversing the wire 44 forming the magnetic coil in the operating circuit. The starter by-pass circuit wires 45 and 46 are connected to the switch tongue 35 and magnet core respectively. The switch tongue 41 is normally held apart from engagement of the core 42 of the magnet by a suitable spring 47, or other convenient arrangement. An auxiliary electric battery 48 40 is installed within the operating circuit for providing energy thereto, or if preferred, the energy for this circuit may emanate from the storage battery 3.

At 49 I have indicated an electromagnetic 45 operated priming means to provide against need of a richer charge of gas being required for the engine to enable it to start readily. As is well known, this may be accomplished in many ways, as for example, by depressing 50 the flushing pin in the carburetor or by operating the choker rod to close the air inlet to the mixing chamber whereby the mixture becomes abnormally rich for priming purposes.

55 There are also many ways of operating such a device electrically, and suffice it to say that the magnet is made to operate such means in any desired manner. This primer is installed in and becomes a part of the operating 60 circuit and will operate instantly upon the closing of the circuit by the thermometer and the clock.

The operation of the device is as follows: Assuming the car to be left alone in the following condition, throttle and spark levers

in starting position, engine switch 38 and starter switch 40 left open as usual, the pointer 22 on the arm 13 positioned opposite the time intervals at which it is desired to have the engine operated, as indicated upon 70 the scale 20, and the thermometer set in accordance with the desired temperature regulation, as upon the scale 29. The engine will remain quiescent till the temperature drops sufficient for the member 25 to engage 75 the end of the thumb screw 27, which will close the electric circuit through the thermometer. Now as the wheel 5 is being constantly rotated by the action of the clock when one of the contact points 10 on the face 80 of the wheel passes under and engages the contact 16 on the end of the arm 13, the clock circuit will become closed. The electric energy then passing through the operating circuit will as before described, automatically 85 close the switch 8 which will complete the circuit therethrough and the connections 45 and 46 through this switch forming a by-pass around the starter switch 40, will close the starter circuit and set the starter motor 90 in instant operation, it being assumed that the leaf valve 34 in the exhaust pipe is maintaining a closed connection between the wires 36 and 37.

If the primer 49 is used in the operating 95 circuit, it will have instantly come into action by electro-magnetic force being generated therein and will supply the necessary priming charge to the engine. Or assuming the engine otherwise properly primed, it will 100 immediately commence to operate as under ordinary circumstances, it being cranked by the action of the starter motor. When now the engine takes hold, that is, starts to operate on its own fuel, the force of the exhaust gases impinging the leaf valve 34 will 105 swing it to a horizontal position, which will separate the arm 35 from contact with the wires 36 and 37 and thus open or break the starter circuit, which will shut down the 110 starter motor. The latter is now passive and the engine proceeds to operate on its own power and will continue to do so until the contact point 10 which first engaged the contact 16 will have passed from under said 115 contact 16 which will open the operating circuit and cause the engine to stop. This cycle will continue to be repeated as the successive contact points 10 revolve about and engage the contacting mechanism, provided 120 however the temperature maintains a closed circuit through the thermometer mechanism, otherwise the starting device would obviously fail to operate.

The necessity of intermittently operating 125 an automobile engine during freezing weather is well understood and does not seem to require further illustration herein.

It is to be understood that various modifications of the mechanism within the scope 130

of the invention may be resorted to without departing from the spirit thereof.

Having thus described my invention what I claim and desire to secure by Letters Patent, is:

1. The combination with an engine furnishing the motive power of a self propelled vehicle and having an electric starter operatively connected therewith, of controlling means comprising a thermostatic circuit maker and breaker, a time operated circuit maker and breaker and means whereby the operation of said controlling means may be predetermined.
- 10 2. The combination with an engine forming the motive power of a self propelled vehicle and having a motor operated starter connected therewith, of means for controlling the starter and the duration of the operation of the engine, means for automatically operating the controlling means and means whereby the automatic operation may be predetermined.
- 15 3. The combination with an engine forming the motive power of a self propelled vehicle and having a motor operated starter connected therewith, of means for controlling the starter, means for controlling the duration of the operation of the engine, means for automatically operating the controller and means whereby the automatic operation may be predetermined and pre-adjusted.
- 20 4. The combination with an engine forming the motive power of a self propelled vehicle and having a motor operated starter connected therewith, of means including a clock and a thermometer for controlling the starter and for timing the duration of running of the engine and means whereby the operation of the controlling means and timing means may be predetermined.
- 25 5. The combination with an internal combustion engine forming the motive power of a self propelled vehicle and having an electric operated starter connected therewith, of

a thermometer, a clock operated mechanism, an automatic switch, means whereby the co-operative action of the last mentioned three elements will start the starter and the starter start the engine, means for automatically stopping the starter, means for subsequently automatically stopping the engine and means whereby the foregoing cycle of operations may be automatically intermittently repeated.

6. The combination with an internal combustion engine and accessories comprising an electric starter, a generator, a storage battery, a starter electric circuit and an ignition electric circuit, of a circuit maker and breaker in the starter circuit automatically operated by the engine, a thermostatically operated circuit maker and breaker and a clock operated circuit maker and breaker installed intermediate of the circuits of the engine and starter and co-operative therewith, a by-pass circuit intermediate the starter circuit and the ignition circuit and an automatic electric circuit maker and breaker in the ignition circuit and controlling the by-pass circuit, substantially as and for the purpose described.

7. The combination with a vehicle engine having an electric generator, a storage battery, an electric starter and an electric circuit therefor, of a co-operative auxiliary electric circuit whereby the electric starter circuit is controlled, said auxiliary circuit having co-operatively installed therein a time controlled switch, a thermostatically controlled switch, an electro-magnetically controlled switch, and an electro-magnetically controlled primer, substantially as and for the purpose described.

In testimony whereof I hereunto affix my signature in the presence of two witnesses.

GEORGE C. OLMSTED.
